DESIGN FOR AN AIR CIRCULATING SPACE
HEATER OR THE LIKE

Robert B. Evans, Grosse Pointe, Eugene F. Farrell
and George M. Schueder, Detroit, Mich., as-
signors to Evans Products Company, Detroit,
Mich., a corporation of Delaware

Application January 24, 1940, Serial No. 89,663

Term of patent 14 years

To all whom it may concern:

Be it known that we, Robert B. Evans, Eugene F. Farrell, and George M. Schueder, citizens of the United States, residing, respectively, at Grosse Pointe, in the county of Wayne and State of Michigan, Detroit, in the county of Wayne and State of Michigan, and Detroit, in the county of Wayne and State of Michigan, have invented a new, original, and ornamental Design for an Air Circulating Space Heater or the like, of which the following is a specification, reference being had to the accompanying drawing, forming a part thereof.

Fig. 1 is a perspective view showing the front and one end of an air circulating space heater or the like, embodying our new design. In this figure, the lid or top is shown open.

Fig. 2 is a partial perspective view similar to Fig. 1 but showing only the upper portion of the space heater or the like, with the lid or top closed.

The other end of the heater is substantially like the end shown, and the back of the heater is substantially plain.

We claim:

The ornamental design for an air circulating space heater or the like, substantially as shown and described.

ROBERT B. EVANS,
EUGENE F. FARRELL,
GEORGE M. SCHUEDER.
